Inventor
Aquila B. Marshall
BY
Conrad Wittenick
his ATTORNEY

UNITED STATES PATENT OFFICE.

AQUILA B. MARSHALL, OF BROOKLYN, NEW YORK, ASSIGNOR TO AMERICAN RADIATOR COMPANY, OF CHICAGO, ILLINOIS, A CORPORATION OF NEW JERSEY.

SUCTION CLEANING TOOL.

Application filed March 4, 1918. Serial No. 220,132.

To all whom it may concern:

Be it known that I, AQUILA B. MARSHALL, a citizen of the United States, residing at the city of New York, borough of Brooklyn, 5 Kings County, in the State of New York, have invented certain new and useful Improvements in Suction Cleaning Tools, of which the following is a full, clear, and exact specification.

10 This invention relates to improvements in suction cleaning tools, and the same has for its object to provide a tool by means of which dirt, waste or other matter may be easily worked up and loosened so as to permit 15 of the same being easily drawn into the suction apparatus connected with said tool.

Further, the invention has for its object to provide a tool of this type with means for effectively dislodging and loosening dirt 20 from the surface to be cleaned.

Further, said invention has for its object to provide a suction cleaning tool by means of which dirt, waste or other matter may be easily and thoroughly loosened from its 25 place of lodgement in the grooves or channels of car floors or other uneven supports, or from the corners and crevices of rooms or compartments, etc.

Further, the invention has for its object 30 to provide a tool of this type with a scraper positioned in advance of its suction or inlet opening.

Further, said invention has for its object to provide a tool of the character specified 35 having a body formed of material which is a non-conductor of electricity in order to protect the user thereof against the effects of the electric current in case the metallic part of the tool accidentally comes into contact with the current conducting means of 40 heating, lighting or other electrically operated apparatus usually employed in trolley cars, railway cars and the like.

Further, the invention has for its object to 45 provide a tool of this type which is efficient in use, easy to handle, and inexpensive and simple in its construction.

Other objects will in part be obvious and in part be pointed out hereinafter.

50 To the attainment of the aforesaid objects and ends my invention consists in the novel details of construction, and in the combination, connection and arrangement of parts hereinafter more fully described and 55 then pointed out in the claims.

In the accompanying drawings showing an illustrative embodiment of the invention, Figure 1 is a perspective view of a suction cleaning tool constructed according to and embodying the invention;

Fig. 2 is a side elevational view of the front end thereof, and

Fig. 3 is a front elevational view thereof.

When using suction cleaning tools of the kind now in general use, it is sometimes found difficult to dislodge or work up dirt which has become caked or hardened in the corners and crevices of rooms or compartments by reason of the fact that the configuration of the tool is such that the matter to be removed from such places cannot be reached. This inability to reach and remove dirt from inaccessible places by the present type of tools is especially true with respect to car floors or the like which are frequently provided with grooves or channels within which dirt or other matter becomes firmly lodged. As the tools now in general use are not adapted to enter such grooves or channels it is difficult to remove the dirt therefrom especially if it has become packed therein, as the suction through the tool is not sufficiently strong to loosen the packed dirt or to lift it from the bottom of the grooves or channels. The object of the present invention, therefore, is to provide a tool, by means of which the dirt or matter may be readily and quickly removed from such confined places, even though it may be firmly adhered to or packed therein.

Referring to the drawing, the suction cleaning tool comprises a tubular body 10, preferably formed of a material such as fibre or the like, which is a non-conductor of electricity, and is of such a size that it may be conveniently held in the hands of the person using the tool.

Secured to, and surrounding the forward end of the body 10 is a ferrule 11 formed of metal, which serves to strengthen the forward end of the body 10 and to act as a wear piece to protect the end of the body 10 from injury by abrasion when the tool is being used. The ferrule 11 is provided with a downwardly extending arm 12 carrying a scraper 13 which is positioned below and extends forwardly of the inlet opening at the front end of the tool.

The scraper 13, which is of a width substantially equal to the diameter of the inlet 110

opening of the tool, has a flat lower or bearing surface 14 and a rearwardly and upwardly inclined front surface 15 forming with the lower surface 14 a knife-like scraping edge 16 at the front of the scraper 13.

In use, the rear end of the body 10 is connected in any suitable manner to the suction hose or flexible member communicating with the suction apparatus.

- 10 In operation, the tool is held in the hands of the operator with the bearing surface of the scraper 13 engaging the surface to be cleaned. As the tool is advanced the knife-like scraping edge 16 of the scraper 13 will loosen, break up, and dislodge any dirt that may be upon the surface being cleaned, and as the dirt is thus loosened it will be drawn into the inlet opening at the forward end of the tool by suction in the usual manner.
- 15 20 The suction cleaning tool above described is particularly adaptable to the cleaning of floors provided with grooves or channels such as are found in cars, for example, as the scraper 13 may be readily inserted within the grooves or channels, and as it travels along the same it will dislodge any dirt that may be therein, thus insuring the due breaking up before the removal thereof by the tool in the manner above described.

25 30 By constructing the tubular body 10 of non-conducting material the operator is fully protected against the effects of an electric current should the metallic ferrule 11 accidentally come into contact with any carrier of electric current which may be located within the car or compartment being cleaned.

35 While the tool is particularly suited for the cleaning of car floors and the like it is, 40 of course, equally well suited for removing dirt from the corners and crevices of rooms or compartments, which dirt or other matter cannot be readily reached and removed by tools of the type now in use.

Having thus described my said invention 45 what I claim and desire to secure by Letters Patent is:—

1. A suction cleaning tool provided with an inlet opening, a relatively-narrow scraper, 50 means for supporting said scraper in position closely below and in advance of said inlet opening, and in a plane forming an angle with the plane of said inlet opening, substantially as specified.

2. A suction cleaning tool provided with 55 an inlet opening, a member secured to said tool adjacent to said inlet opening, a relatively narrow scraper positioned closely below and in advance of said inlet opening, and in a plane forming a right angle with 60 the plane thereof, and means for supporting said scraper upon said member and in spaced relation to the inlet opening of said tool, substantially as specified.

3. A suction tool comprising a tubular 65 body provided with an inlet opening, an annular member embracing the end of said tubular body, a downwardly extending arm secured to said annular member, and a scraper at the lower end of said arm extending forwardly therefrom in advance of 70 said inlet opening, substantially as specified.

4. A suction tool comprising a tubular body provided with an inlet opening at its 75 forward end, the plane of said opening being at right angles to the axis of said tubular body, a downwardly extending arm secured to said body adjacent the forward end thereof, and a scraper at the lower end 80 of said arm and extending forwardly therefrom in a plane forming a right angle with the plane of said inlet opening, substantially as specified.

AQUILA B. MARSHALL.
